UNITED STATES PATENT OFFICE.

JOHN H. HORSBURGH, OF CLEVELAND, OHIO.

WRENCH.

Application filed January 17, 1923. Serial No. 613,084.

This invention relates to wrenches, and particularly to that class of wrenches having a movable jaw, shiftable toward a fixed jaw by means of a handle, actuating an intermediate element having toothed engagement with said movable jaw.

The object of my invention is to provide a wrench of this character in which the jaws are readily adjustable, one with the other to grip objects of varying sizes. One common weakness in wrenches of this class heretofore made is that the parts are apt to be too delicate and therefore lack sufficient strength for their intended use. My structure now to be disclosed overcomes this difficulty without enlarging the parts, or increasing their number—in fact, the device is somewhat simplified while its strength is increased.

Another object of my wrench construction is to make use of the usual third class lever for the handle member in operating the wrench, while at the same time increasing greatly its leverage and thereby its power, by positioning its fulcrum much nearer the movable jaw than has been heretofore thought possible. As well understood in devices of this class, the fulcrum for the handle lever is situated within a casing, and difficulty has been encountered in mounting the fulcrum high enough in the casing to provide a sufficiently short arm for the lever without weakening the lever. This has arisen from the fact that the intermediate part for directly engaging the movable jaw member must be carried by the said lever, loosely and movable thereby, so that the movable jaw can be quickly adjusted to different positions and thus to different sizes of nuts or pipes. I have succeeded in mounting the fulcrum of my lever handle as high as desired without interfering with the movement of said intermediate member and without weakening any of the parts.

A further object of my improved device, is to provide the intermediate actuating part for the movable jaw in the form of a slidable dog having a toothed edge engaging the movable jaw element, the said toothed edge having two sections continuous, one with the other, one of which is curved on an arc concentric with the fulcrum of the lever, and the other arranged in a straight line, there being a plurality of said lineal teeth in engagement when the nut or pipe to be turned is gripped by both jaws, and the

said arc teeth engaging the jaw while adjustment is being effected. This will be fully explained in the following description, and is especially urged as a feature, further lending great strength and rigidity to the device.

These and other objects of my invention will appear in connection with the following detailed description thereof, as set forth in the appended claims, and as disclosed in the accompanying drawings in which:

Figure 1 is a side elevational view of the wrench with the face plate removed;

Figure 2 is a section of the wrench taken on the line 2—2 of Fig. 1;

Figures 3 and 4 are side elevations and perspective views, respectively, of opposite sides of the face plate;

Figure 5 is a plan view of the device with parts broken away to show a section taken on the line 5—5 of Fig. 1; and

Figures 6, 7 and 8 are perspective views of detailed parts of the movable jaw and actuating means therefor.

Similar reference characters indicate corresponding parts throughout the several views.

1 designates the body part which is formed as a hollow casing constructed of plates 2 and 3 which are secured together by rivets 4 when the parts are assembled. Integral with plate 2 is the fixed jaw 5 having stepped edges 6 and 7 at its lower horizontal, overhanging part, and the usual vertical gripping face 8. Plate 3 has an upper projecting ear 9 which fits under 7 snugly, and is provided with side ribs 10 which meet corresponding ribs 11 on plate 2 as shown. By this construction a hollow casing is provided having a transverse slot 12 and a longitudinal slot 13, the former receiving therein a plate or shank 14 integral with the movable jaw 15 and having a guiding bead 16 sliding in a groove 17 in the inner face of the plate 3, and its upper edge snugly fitting the lower step 6 of jaw 5.

This groove 17 reaches the edge of plate 3 under the jaw 5, but is spaced from the edge of plate 3 beneath jaw 15, thus providing a stop 18 against which the end 19 of bead 16 strikes in the desired extreme throw of the shank 14. The latter has teeth on its lower edge which are actuated as will be later on explained. Through the slot 13 a handle member 20 enters, the upper end thereof being provided with yoke arms 21

which are connected together and strengthened by a web 22 integral therewith. As this web is thinner than the arms, a socket 23 is thus formed for receiving therein an actuating dog 24 later to be described.

Since the socket 23 is designed to control the dog 24 very accurately, even when the latter is movable longitudinally of the handle or lever 20, this socket is provided with a curved closed end 27, which for convenience may be termed the lower end, straight arms and an open end at the extreme inner end of the lever within the body 1. On the face of the web opposite the socket, and adjacent to its upper edge, is a pin 25 integral with said web and designed to serve as the fulcrum of the lever 20. An aperture 26 is made in the plate or wall 2 of the body portion to receive this pin and is positioned as close to the shank 14 as possible, without incurring the disadvantage of any portion of the lever contacting with the shank when the lever swings laterally as far as the ends of the ribs 10 and 11 on the plates or walls 2 and 3 of the body.

The actuating dog, before referred to, is a flat metal plate having straight edges terminating at one end in a curve 28 fitting accurately the curve 27 of the socket. The opposite end of the dog is provided with teeth adapted to register with teeth 29 on the shank of the movable jaw member, when the parts are in engagement. The parts 27 and 28 are normally separated by the pressure of the compression spring 30 seated in sockets in the dog and lever as shown clearly in Figs. 1 and 2. The latter construction holds the toothed portion of the dog normally in engagement with the rack teeth 29, though it will be noted that the major portion of the dog will, in all cases, lie in contact with and form a part of the long arm of said lever 20, being below the said pin 25, only the small margin of the dog adjacent its teeth rising above the fulcrum and forming the short arm of this lever of the third class. This construction provides a very powerful leverage, since the toothed arm is so short relative to the long arm or handle thereof. It has been considered difficult to attain heretofore, because of the danger of splitting the legs or arms of the part enclosing the other, whether such arms are on the dog or the lever. But this latter difficulty I have obviated by providing the web 22, as before explained, both strengthening the arms of the lever and providing a means for positioning the fulcrum close to the rack 29.

Fixed to the dog and on the side thereof opposite the pin 25, but concentric therewith, is a pin 31, having an enlarged end 32 which is designed to protrude through the elongated slot 33 in the plate 3, whereby pressure applied to 32, against the force of the main

spring 30, may disengage the dog from the shank, and thus separate the teeth on the dog from rack teeth 29. The said slot 33 is elongated vertically and is also widened at its base, as shown clearly in Figs. 3 and 4, to permit unobstructed movement of pin 31 therein whether the dog 24 carrying such pin is in the socket 23 when the latter is in either of the positions shown in Fig. 1, or one intermediate the two.

The teeth 29 on the shank 14 form a continuous rack and are shown in these views as ratchet teeth, though they need not be restricted to that form. The teeth on the dog 24 are, however, formed in two sections, one continuous with the other, the section in use for adjustment of the movable jaw to different sizes of nuts or pipes being curved on an arc 34 concentric with the pin 31 and operating in much the same manner as a gear sector, while the toothed section in engagement with the rack 29 when greatest power is exerted in applying twisting strain, is straight and designated by numeral 35 (see Fig. 7) and thereby provides for utilizing a plurality of teeth in engaging said rack 29, when great power is needed most.

It will thus be seen that the arc section is in engagement with the rack when the handle is in the dotted line position in Fig. 1, but the lineal section in use when the handle is in its position shown in full lines of said view.

It is further to be noted that the pin 25 is positioned somewhat lateral of the midpoint of the width of said web 22, for the purpose of providing a common radius for the said arc. Figs. 1 and 8 of the drawing show clearly also that the yoke end of the lever is shifted somewhat laterally of its length, so that the pin 31, and fulcrum 25, are not in alignment with the axis of the handle, the latter condition resulting from the same cause. While it was stated heretofore that the pin 31 is concentric with pin 25, this is only true when the dog 24 is in its normal position in the socket 23 by reason of the upward pressure of the spring 30. When a downward thrust is given to the part 31, as before explained, the latter part will of course descend into the socket and out of alignment with the fulcrum of the lever.

It will be evident that the automatic upward thrust of the dog by reason of said spring will enable the teeth on the latter to slip past the rack teeth 29, especially if such teeth are of the ratchet type, and a new grip on the shank may thus be attained whereby the movable jaw 15 will be adjusted for engaging a smaller object. If the wrench is intended for use upon polygonal parts such as nuts, or the like, it is often quite desirable to provide the left hand side of the yoke end of the lever with a compression spring 37 as shown in Fig. 8 to

normally hold the handle in the dotted line position of Fig. 1. If, however, it is designed to use my wrench upon pipes, as in plumbing, it will then be found expedient to mount the said spring upon the right hand side of said yoke end to normally hold the lever in the full line position of Fig. 1. Also, in such use, it will also be desired to provide both jaws 5 and 15 with gripping teeth, as well understood in such art. Such toothed construction and the reversal of the spring 37, as above explained, is so common and so elementary in this art that it is not thought essential to illustrate the same, especially since such slight modification is not now believed to be patentable and no claims are herein directed to that feature.

Because of the said offset position of the yoke end of the lever, the right hand side 20 of such end is hollowed out at 36, as shown in Fig. 8, to fit the curved lower end of the web 11, at the extreme throw of the handle.

In the operation of the device as above described it will readily be seen that if the wrench be held in the hand vertically with the jaws extended upwardly, a downward thrust of the thumb upon the head 32 will disengage the dog from the rack, when the movable jaw member will slide loosely in its either direction but will be limited in its open position by the parts 18 and 19. The jaws may be positioned about a nut or pipe approximately close to its sides when the handle is in the dotted line position, when releasing the pin 31 will cause the dog to engage the rack and the usual movement of the handle 20 will tighten the jaws for a powerful gripping effect—especially strong in my construction because of the very high position of the fulcrum 25; and this severe strain will not injure the yoke because of the strengthening web 22 which is integral with the arms 21.

Other advantages of my invention will be apparent to those who are skilled in the art to which it appertains.

Having thus described my invention, and the manner of its operation, what I claim as new and desire to secure by Letters Patent is,—

1. A wrench comprising fixed and movable jaws, a handle having spaced yoke arms integral therewith, a web integral with said arms, a fulcrum element on said web, and locking means for the movable jaw adapted to be actuated by said arms.

2. In a wrench, an actuating member having spaced yoke arms and an integral web connecting said arms, in combination with a pivot pin mounted on said web.

3. A wrench, comprising a fixed jaw, a movable jaw, a handle operatively connected with the movable jaw to adjust the latter, and having upwardly extending yoke arms 65 at its upper end, a web integral with and

connecting said arms together, means on said web for pivoting the said handle on the body portion, and means actuated by said yoke arms, for locking the movable jaw in its adjusted position.

4. A wrench, comprising a body portion having a fixed jaw, a movable jaw on the body portion, a handle member having yoke arms at one end thereof and a connecting web integral therewith and joining said arms thereby forming an open socket, a pin integral with said web and pivoted in said body portion, and a locking member seated in said socket and actuated by said yoke arms and normally interlocking with said movable jaw to maintain the latter in its adjusted position.

5. A wrench comprising a body portion having a fixed jaw, a movable jaw, a handle operatively connected with the movable jaw to adjust the latter and having means thereon adjacent its upper edge pivoted on the body portion, and a locking member slidably mounted on said handle with its major portion extending below the pivot of the handle, and actuated pivotally by the latter to lock the movable jaw in its adjusted position, and a stud mounted on said locking member normally concentric with said pivot and projecting oppositely therefrom for actuating the said member slidably on the handle.

6. A wrench comprising fixed and movable jaws, a handle having yoke arms integral therewith but spaced from each other, a web connecting the arms, a fulcrum element on said web, a locking member slidably between said arms and upon the face of the web for actuating the movable jaw, and a stud mounted on said locking member normally concentric with said fulcrum projecting oppositely from the web for actuating the slidable member.

7. A wrench comprising fixed and movable jaws, a handle, a locking member for the movable jaw connected slidably with said handle for common actuation, one of said elements having spaced yoke arms integral therewith, a web integral with said arms, a fulcrum element on said web, and the other element engaging said arms.

8. A wrench having a body provided with transverse and longitudinal slots therethrough and a jaw integral therewith, a movable jaw having a shank at right angles thereto movable in said transverse slot and having ratchet teeth formed thereon, a handle movable in said longitudinal slot and having yoke arms at one end thereof, a thin web integral with and connecting together the said arms, thereby forming a socket, a pin on said web projecting into an aperture in said body for pivoting the handle thereon, a spring actuated dog mounted in said socket and movable on and with said han-

dle, and teeth formed on said dog for engaging said ratchet teeth for locking said shank and movable jaw in fixed positions.

9. A wrench having a body provided with transverse and longitudinal slots therethrough and a jaw integral therewith, a movable jaw having a shank at right angles thereto and movable in said transverse slot, said body having a groove in one of its walls on the inner surface of said transverse slot extending part way across said slot and parallel therewith, and said shank having a rib on one of its sides parallel therewith but shorter than the shank, for moving in said groove, a handle having yoke arms at one end, a web connecting said arms and forming with the latter a socket, said handle being movable laterally in said longitudinal slot, a pin integral with said web pivoting the said handle in a wall of said body, rack teeth formed on said shank, a spring-actuated dog seated in said socket and movable longitudinally therein, teeth formed on said dog for engaging said rack teeth for locking said shank and movable jaw in fixed positions and for releasing the same, said body having an elongated slot in one side, and a headed stud projecting through said slot and rigid with said dog for actuating the latter.

10. A wrench, comprising a fixed jaw, a movable jaw, a handle operatively connected with the movable jaw to adjust the latter, and having yoke arms at one end thereof and a connecting web integral with and joining said arms thereby forming an open socket, a locking member seated in said socket and actuated by said yoke arms, a spring within said socket below said locking member for normally urging the latter upward into interlocking engagement with said movable

jaw to maintain the latter in its adjusted position, a pin integral with said web near its upper edge and pivoted in said fixed jaw member, said locking member having on its upper edge gear teeth comprising straight and curved sections, the latter formed in an arc concentric with said pin when the locking member is in normal position, and the upper end of the handle being offset from the axis of the handle to provide for said concentric relation.

11. A wrench, comprising a body portion provided with a stationary jaw, a movable jaw member on said body portion, a handle operatively connected with said movable jaw member to adjust the latter relatively to the stationary jaw, fulcrum means on said handle adjacent its upper edge and said movable jaw member for rocking in an aperture in said body portion, a locking member slidably mounted on said handle with its major portion extending below said fulcrum means and a narrow edge portion projecting beyond said fulcrum means, said narrow portion having teeth thereon for engagement with said movable jaw member, said teeth comprising two sections, one of which is straight, and a curved section continuous with the straight section, the latter formed as an arc which is concentric with said fulcrum when the locking member is in normal position on said handle, means for normally urging said locking member towards the said movable jaw member, and a pin fixed on said locking member and protruding through a slot in said body portion for manually disengaging said locking member from the movable jaw.

In testimony whereof I hereunto affix my signature.

JOHN H. HORSBURGH.
